CONDENSATION OF HYDROCARBONS

Filed July 15, 1942

UNITED STATES PATENT OFFICE

2,422,443

CONDENSATION OF HYDROCARBONS

William Alvah Smith, Pittsburgh, Pa.

Application July 15, 1942, Serial No. 450,966

1 Claim. (Cl. 196—78)

1

This invention relates to the chemical condensation of mineral hydrocarbons of relatively small complexity into hydrocarbons of relatively greater complexity, and is in the nature of an improvement upon my prior copending application Serial No. 426,602, filed January 13, 1942, now U. S. Patent No. 2,356,952 granted August 29, 1944.

In my said prior application, I have disclosed an improved method and apparatus for treating petroleum oils, particularly crude oils, to increase the percentage of light bodied lubricants by controlled conversion. However, certain crude oils, such as California crude oils, contain relatively large amounts of light bodied lubricating components, but are deficient in heavy bodied components, such as are deemed desirable, for example, in the lubrication of aircraft engines, and it is frequently desirable to treat petroleum hydrocarbons of relatively small complexity, particularly light bodied lubricants and the lighter fractions distilled off in the treatment of crude oils, in order to condense such hydrocarbons into heavier bodied hydrocarbons, such as those of greater complexity.

An object of this invention is to provide an improved method and apparatus for changing mineral hydrocarbons, particularly petroleum, of relatively small complexity into hydrocarbons of greater complexity, which will be relatively simple, practical, inexpensive, and rapid, which will require a minimum of apparatus, and which will utilize apparatus that is relatively simple and inexpensive.

Another object of the invention is to provide an improved method and apparatus for condensing mineral hydrocarbons of the petroleum type into hydrocarbons of greater complexity, which will produce hydrocarbons of the desired complexity of a high quality and at a relatively low cost.

Other objects and advantages will be apparent from the following description of some embodiments of the invention, and the novel features will be particularly pointed out hereinafter in connection with the appended claim.

In the accompanying drawings:

Fig. 1 is a diagram illustrating schematically an elevation of a simple form of apparatus which may be employed in the practice of this invention; and

Fig. 2 is another elevation illustrating diagrammatically a simple form of apparatus for use in the chemical condensation of the hydrocarbons not in liquid form at ordinary room temperatures and pressures.

2

Chemical condensation of various compounds is well understood in the industry and might be briefly designated as the opposite or converse of cracking when applied to petroleum hydrocarbons. In other words, condensation is a reaction by which the atoms in the same or different molecules are combined to form a new compound of greater complexity and frequently of greater molecular weight or density.

10. I have discovered that mineral hydrocarbons, such as those of petroleum, and of relatively small complexity, may be condensed into hydrocarbon compounds of greater complexity by heating said hydrocarbons to be condensed, to a temperature 15 above approximately 400° F., but less than the temperature which causes degradation of the hydrocarbons, while maintaining such hydrocarbons in intimate contact for a substantial period of time with a condensation agent, such as acid-activated clay and heat activated bauxite, and prior to the completion of this contact, halogenating the hydrocarbons. After the chemical condensation, the condensed hydrocarbons are separated from the condensation agent in any suitable manner. Preferably, the halogenation is accomplished prior to the contact between the condensation agent and the hydrocarbons, but not necessarily so.

30. Specific examples of this invention will now be described:

As one example, a crude oil such as California crude oil, is first halogenated in any suitable manner, such as, for example, by passing hydrogen chloride gas through the oil under proper 35 temperature conditions, during which a considerable amount of the gas is absorbed by the oil. This halogenated material is then mixed with finely divided, acid-activated clay or heat-activated bauxite, in which preferably is also mixed

40. a metallic compound, such as cuprous oxide. This mixture is then heated in any suitable manner, such as by pumping it through a pipe still, in which the mixture is heated to a temperature above approximately 400° F. and below 45 that which would cause degradation of the hydrocarbons. The resulting, chemically condensed part is then separated from the catalysts or condensation agent in any suitable manner. 50. If the mixture of the halogenated hydrocarbon and the condensation agent is pumped through a pipe still, the different fractions may be separated in the still, or the condensed hydrocarbons which are vaporized at the still temperatures, may be all 55 passed over and physically condensed into a com-

mon receiver and then later separated into the desired fractional components.

The portion of the oil, after such treatment, which passes off with the condensation agent may then be separated from such agent, such as by filtering, and the agent revivified and re-used. While the hydrocarbons to be treated are, in this example, halogenated or mixed with the hydrogen chloride gas before being mixed with the condensation agent, it will be understood that the halogenating medium may be admitted to the hydrocarbons at any point in the treatment prior to completion thereof. Better results appear to be obtained when the halogenation occurs before the mixture with the condensation agent, or at least early in the heat treatment of the hydrocarbons with the condensation agent. This gives an increase in the heavier oils, and is really a synthesis of the heavier oils, rather than cracking.

When one desires to chemically condense mineral hydrocarbons that are too volatile to be handled as a liquid in the treatment, these volatile hydrocarbons are halogenated as such under the proper temperature conditions and subjected at the same time, or subsequently, to condensation by bringing them during halogenation or subsequently thereto into intimate or prolonged contact with the condensation agent, such as in pellet form. During the treatment with the condensation agent, the hydrocarbons are heated to a temperature above 400° F., but less than the temperatures which would cause degradation of the hydrocarbons or prevent chemical condensation, and then after the hydrocarbons are chemically condensed, they may be physically condensed into liquids and separated, either by condensing them separately from the condensation agent, or by filtering the same after the agent is added, or in any other suitable manner.

As another example of the invention, the hydrocarbons may be brought into intimate contact with the condensation agent and a metallic chloride or an available halogen in the presence of heat, as explained in the other two examples above, and the halogen in the form of hydrogen halide appears to be liberated from the metallic compound so as to perform the halogenation of the hydrocarbons during the reaction in the presence of condensation agents.

Any suitable condensation agent may be employed, but preferably I employ a product containing aluminum, such as acid-activated clay or heat-activated bauxite, as the condensation agent. I have also found that better results are usually obtained, if one incorporates in the acid-activated clay or the heat-activated bauxite, an additional finely divided metallic compound, such as, for example, various compounds of iron, copper, aluminum, zinc and nickel.

The condensation action is also sometimes improved if the halogenated hydrocarbon is brought into contact with the condensation agent while mixed with some other unhalogenated substance, such as benzol, or other hydrocarbons. Such an action is illustrated by the following equation:

I have found that the best results were obtained when the condensation agent had intermixed therewith a cuprous oxide (Cu_2O), although good results were obtained with cupric oxide (CuO), and with iron sulfate and oxides. When the halogenation is to occur during the treatment

with the condensation agent, I have found that excellent results are obtained by using copper and iron chlorides intermixed with the condensation agent, and the cuprous chlorides appear to be superior to the cupric chlorides. When using the copper chloride with the acid-activated clay, for example, the clay appeared to permit the copper chloride to evolve chlorine in the form of hydrogen chloride, with some halogenation of the organic material. Clay is an impure aluminum silicate containing impurities including iron, and bauxite is a form of aluminum hydroxide, rather impure and also containing iron. Bauxite is activated usually by heat to about 1000° F. The metallic impurities in bauxite and clay, of which iron is a prominent example, appear to aid in the condensation reaction, but such action is in some instances apparently expedited by the addition to the clay or bauxite of the other finely divided metallic compounds, such as those hereinbefore mentioned.

The make-up of the condensation catalyst or agent will depend to some extent upon the nature of the materials to be condensed, but as a general rule, the acid-activated clay and heat-activated bauxite are each preferably used with the metal compound. The metal compound is usually in the form of an oxide if a reactive atom, such as chlorine, exists on the materials to be contacted, but if the materials to be contacted contain double bonds or some similar condition, the desirable component, such as metallic chlorides or other metallic halogens, may be incorporated with the metal, if so desired.

The condensation agent employed with either of these examples, after use, may be revivified by any of the usual methods known in the industry, and by properly adjusting the various components, continuous operation and regeneration is feasible with a minimum expenditure of reagent and utilities. With this invention, the large amount of cracked gases obtained from cracking processes may be converted into superior automotive fuels, or even heavier products, or both.

The temperature range of the hydrocarbons during chemical condensation is usually between 400° F. and 680° F., nearer the latter, as measured with the thermometer bulb immersed in the mixture. It is believed that the actual temperature at the heating surface may be a little higher because in the application of the process by means of a pipe still, the transfer line temperatures to secure similar results may be about 80° higher. The temperature to be used is readily determined experimentally for a given desired reaction, but if the temperature is too high, it causes degradation of the materials by cracking, and thus interferes with the condensation.

Referring now to the drawings, the apparatus shown in Fig. 1 is intended to be diagrammatic and illustrates the principle of the invention when a pipe still is employed. In this apparatus, the mixture of oil and the finely divided condensation agent is supplied through the reservoir 10. This mixture is withdrawn therefrom by pipe 11, controlled by valve 12, through the action of a pump 13. The pump 13 delivers the mixture under pressure through the pipe 14 into one end of a coil 15 which is disposed in a heating chamber 16. The other end of the coil is connected by a pipe 17, controlled by valve 17a, to a reaction or flash chamber 18 having, if desired, a plurality of fractionating chambers 1, 2, 3 and 4. This flash chamber 18 extends downwardly through a heating chamber 19.

5

A pipe 20 controlled by a valve 21 opens out of the bottom of the chamber 18, so as to remove the condensation agent and the heavier hydrocarbon components, and this removed mixture is separately treated, such as by filtration, to separate the condensation agent from the liquid medium in which it is carried and which represents the heavier hydrocarbons. The chambers 16 and 19 are heated in any suitable manner, such as by passing hot gases into the lower end of the chamber 16 through conduit 22 and removing them at the upper end through a pipe 23 controlled by a valve 24. The chamber 19 may be heated by passing hot gases into the same through a flue or pipe 25 controlled by a valve 26, and removing such hot gases from the bottom of the chamber 19 by a flue 27 controlled by a valve 28. The chambers 16 and 19 may advantageously be provided in a common casing in which the chambers are separated by a partition 29 having an opening 30 therein adjacent the upper end thereof, and this opening 30 may be closed or opened to any desired extent, such as by a slide valve 31.

The pipe 17 has a branch 17b before its connection to the valve 17a, which branch after passing through a valve 32 subdivides into a plurality of pipes 33, 34, and 35, controlled respectively by valves 36, 37 and 38, leading to the upper ends of the fractionating chambers 1, 2 and 3. The pipe 17b also has a branch pipe 39 which is connected to a pipe 40 that leads from the upper end of the top fractionating chamber 4 to the upper end of a physical condensation coil 41. The lower end of the coil 41 is connected by a pipe 42 to a reservoir 43 which receives the condensation products. The coil 41 is disposed in a casing 44, and a cooling medium enters the chamber of the casing 44 through an inlet pipe 45 at the bottom, and is removed through an outlet pipe 46 adjacent the top of the casing 44. The fractionating chambers 2, 3 and 4 may have overflow pipes A, B and C respectively, which lead to separate cooling devices 47, 48 and 49 respectively. This fractionating tower may have any desired number of chambers and may be otherwise constructed in accordance with the usual practice in the oil industry.

If the liquid hydrocarbon to be condensed in this manner is not previously halogenated, the halogen is added to the mixture either in the receptacle 10, or in the pipe 14 by a pipe 53 controlled by valve 51. If desired, water or a readily vaporizable hydrocarbon, such as gasoline, may also be added to pipe 14 alone or with the halogen through the pipe 53. Steam or gasoline, or even a halogen gas may also be added through a pipe 51a to the lower end of the reaction or flash chamber 18. The outlet from the upper end of the chamber 4 to the pipe 40 may also be provided with a valve 53 at a point below the connection between pipes 39 and 40. By suitable manipulation of the valves, the condensation may be carried on and part of the overhead separated by fractionation into different components through the outlet pipes A, B and C, or all of the overhead may be carried over by the pipe 40 and condensed in the coil 41. This combination overhead is then treated subsequently in any suitable manner to separate off individually the different fractions.

In Fig. 2, a simple form of apparatus is illustrated for handling mineral hydrocarbons in vapor form, which are to be condensed, and in this example, a steel tube 55 is disposed in as-

6

cending or upright position and connected at its upper end to an intake pipe 56 by which the hydrocarbons in vapor form are admitted under pressure to the upper end of the tube 55. The tube is filled with the condensation agent or catalyst in pellet form, this column of pellets resting upon one or more apertured plates 57 in the tube. The lower end of the tube 55 is connected by a tube or conduit 58 to a receiver 59, but the tube 58 passes through the chamber of a condenser 60. For this purpose, the tube 58 is surrounded by a liquid-tight casing and a cooling medium is circulated through this casing around tube 58 so as to chill and physically condense the vapors in the tube 58. The physically and chemically condensed hydrocarbons are then discharged through the lower end of the tube 58 into the receiver 59.

The tube 55 is surrounded, along its length, with a plurality of separate heating chambers 61, 62 and 63 and these chambers may be heated in any suitable manner, such as, for example, by electric heaters with a thermostatic temperature control, so as to selectively control the temperature throughout the whole length of the tube 55. The hydrocarbons to be condensed enter the top of the tube 55 and during their descent through the tube 55, they pass in prolonged contact with the condensation agent. The chemically condensed material is also physically condensed during its descent or in the tube 58. I have found that five or six pounds per square inch pressure on the ingoing vapors is usually sufficient. It will also be understood that liquid hydrocarbons to be condensed chemically may also be passed downwardly through the tube 55 in the same manner as the gases, and they also will be chemically condensed in a similar manner to that of the vaporous hydrocarbons.

Where the hydrocarbons to be treated are first halogenated, the condensation agent or catalyst may be one free of a halogen, such as the acid-activated clay or the heat-activated bauxite in finely divided but solid form, such as in pellets. Where the hydrocarbons are not first halogenated, the metallic chlorides are incorporated either in the pellets containing the agent, or in separate pellets intermixed with the pellets containing the condensation agent, or otherwise distributed along the path of the hydrocarbons, so that the hydrocarbons in passing through the apparatus will be subjected to the action of the halogen as well as the condensing agent. The metallic compound when used will be incorporated in the pellets, or in separate pellets intermixed with the pellets of the condensation agent.

It will be understood that various changes in the details, materials and arrangements of parts, and in the different steps, which have been herein described and illustrated in order to explain the nature of the invention may be made by those skilled in the art within the principle and scope of the invention, as expressed in the appended claim.

65 I claim as my invention:

The improved method of chemically condensing petroleum hydrocarbons of relatively small complexity into hydrocarbons of relatively greater complexity which comprises treating said hydrocarbons of small complexity with hydrogen chloride gas, bringing the treated hydrocarbon into contact, at approximately the same time and for a substantial interval, with acid-activated clay and an oxide of copper, and while at a temperature above approximately 400° F. and below

that which would cause degradation of the hydrocarbons, and separating the chemically condensed product from the clay and copper oxide.
